DERMATOID MASK

Elizabeth Dohm, Toledo, Ohio, assignor of one-half to Florence R. Seyfried, Toledo, Ohio

Application October 18, 1934, Serial No. 748,786

8 Claims. (Cl. 128—163)

My invention has for its object to provide a porous, dermatoid mask which may be used to increase the efficiency and effectiveness of lotions, creams, astringents, and the like, commonly used by beauticians for skin rejuvenation.

My invention particularly has for its object to provide means whereby the patient may move about freely, have full use of the eyes and lips, and remain in an upright position during the rejuvenating process without harm to the face or without loss of the beneficial qualities of the preparations used in the process.

A still further object of my invention is to provide a mask having definite, inherent corrective qualities whereby the skin is stimulated and massaged, and various facial and neck muscles are strengthened, thereby improving the facial contour.

The invention consists in other features and advantages which will appear from the following description and upon examination of the drawing. Structures containing the invention may partake of different forms and still embody the invention. To illustrate a practical application of the invention, I have selected a dermatoid mask as an example of the various structures and details thereof that contain the invention and shall describe the selected dermatoid mask hereinafter, it being understood that variations may be made without departing from the spirit of the invention. The particular dermatoid mask selected is shown in the accompanying drawing and described hereinafter.

Fig. 1 is a perspective view of the dermatoid mask, the mask being shown in position on the user's face. Fig. 2 is a side view of a part of the mask.

Treatments of the face involving various creams, lotions, astringents, massage, and other processes well-known in the field of dermatology have been commonly used in the corrective treatment of various skin diseases, such as acne, and for purposes of skin rejuvenation. Heretofore, however, such treatment has necessitated that the patient remain in an unnatural position during the necessary, long periods of treatment and has often caused great inconvenience to the patient. Much of the value of such treatment has been lost because medication is ordinarily applied under pads of cotton or the like, and these pads may easily be displaced in spite of the efforts of the beautician and the patient.

With the dermatoid mask of my invention, the use of such unsatisfactory pads is eliminated in applying corrective preparations to the face.

The medication is placed on the skin, and when the mask is applied, the patient is able to walk about freely without loss of the value of the medication, and the construction of the mask is such that it adheres to the skin, and by the involuntary action of the muscles of the face the skin is gently and constantly massaged, thereby increasing the effectiveness of the medication applied.

An important element of skin rejuvenation is the tightening of sagging facial muscles and the correct positioning of them with respect to the bony structure of the face. Such adjustment of the muscles cannot be accomplished by the mere use of astringents or facial clays or packs. Wrinkles on the face, particularly about the nose, mouth, and eyes, cannot be permanently removed by the sole use of astringents and like preparations, since such conditions are often the result of sagging muscles or muscles needing adjustment. By the use of the dermatoid mask, the beautician is able to position correctly the important muscles of the face which control the facial contour before finally fastening the mask in position. The facial muscles are held in position by the mask and by reason of its construction are tightened and adjusted to improve the facial contour.

In the form of construction shown in the drawing, the mask 1 is constructed of a porous, elastic rubber, or it may preferably be constructed of porous, elastic material having relatively rough and uneven surfaces, which, in combination with the construction of the mask, cause the mask to frictionally engage and hold the skin in its adjusted position relative to the inner surface of the mask when the mask is fastened in place by suitable means. If desired, the mask may be constructed of any suitable material having pores and adapted to fit the face firmly and adhere to the skin of the face, at the same time having the required degree of elasticity. The mask may be molded, or it may be constructed from a sheet material to conform to the contour of the face and the formation of the various reinforcing parts accomplished by molding, seaming, or by over-lapping and fitting through pressure means. The mask is provided with suitable openings 2 for the eyes and the openings 3 and 4, respectively, for the nose and mouth. The openings 2, 3, and 4, are such that while the patient is able to use the eyes, nose and mouth without discomfort, the mask fits firmly about these areas, and the effectiveness of the corrective work of the mask is not lost.

After the desired medications or lotions are applied to the face, the mask is placed on the face and fastened in position by the tension members or adjustable straps 7, 8, and 9 of well-known construction. The various facial muscles needing corrective treatment may then be pushed into position by the beautician and the adjustable neck band 10 fastened about the neck. The position of the tension members 7, 8, and 9, at the side edge portions of the mask is such as to draw from central portions of the mask, and due to the shape of the mask and the tension exerted by the members 7, 8 and 9, the muscles are held firmly in place when the mask is fastened, without danger of the muscles slipping from their position. By the involuntary action of the muscles of the face and neck in combination with the shape and material of the mask there is produced a gentle and constant massage about the face and neck, which increases the effectiveness of the medication applied to the face and assists in firming the weakened and sagging muscles. The massage stimulates the blood and increases the circulation, which is necessary for the firming of muscles and the building up of the facial tissues. The stimulation to the skin of this massage increases the benefits of the medications applied and eliminates the need for manual massage. Also, if the mask is worn regularly, the massage breaks down the excessive fatty tissue about the face and neck, thereby facilitating reducing.

In order that the mask may efficiently firm sagging muscles and remove face wrinkles, the mask is provided with various yieldable, tension distributing ribs and reinforcements by which are created defined areas and lines of pull which coincide in direction and location with the important face and neck muscles. The ribs and reinforcements may be made by over-lapping the material or by molding and have their source at the points of connection of the adjustable straps to the mask, which are the points of greatest pull.

The adjustable strap or tension member 9 is fastened as by a ring 12 to the fan-shaped portion 13, from which extend tension distributing ribs 14 and 15 and the reinforcing member or rigid rib 16. The ribs 14 and 15 are tapered as at 17 both in thickness and in width, thereby creating the area of greatest firmness and pull about the chin and jowl, and effectively firming and tightening the digastricus, the triangularis, the mentalis and the mylohyodeus muscles. The direction and size of the ribs 14 and 15 are such that the lines of pull will assist in the breaking down of objectionable fatty tissue about the jaw bone and improve the contour of the face. The rigid rib 16 holds the neck band 10 in place against the pull exerted by the elastic ribs 14 and 15, and holds various chin and jowl muscles in place and assists in the elimination of unsightly wrinkles about the face and neck.

In order to strengthen and firm the orbicularis oculi muscles, tension distributing ribs 19 and 20 are formed on the mask and have their source at the fan-shaped member 18 to which is attached, as by a suitable ring 12, the adjustable strap 8. The ribs 19 and 20 taper in width and thickness, and due to their construction and their relation to the tension member 8, form a definite area of pull about those parts of the orbicularis oculi which most commonly sag. By the construction and positioning of the elastic ribs 19 and 20, the area of greatest pull lies in the plane between

the ribs, and consequently the wrinkles about the eyes, commonly known as "crows feet", may be eliminated by the regular wearing of the mask. The area of tension is such that the muscles about the eyes and upper cheek are tightened and correctly positioned to eliminate unsightly wrinkles and to improve the appearance about the eyes. 5

The respective positions of the ribs 14 and 15 are such that they coact to produce a definite 10 tension line across the cheek in the same line and direction as the zygomaticus muscle. The upward pull that is exerted by the rib 19, due to its relation with the rib 14, tightens and firms the zygomaticus muscle which crosses the cheek 15 diagonally and passes under the lower lip. The firming of this muscle not only corrects the sagging of the cheek, but materially improves the appearance of the lips and the contour of the chin.

The rib 19 is also so positioned that a definite 20 upward pull is exerted between it and the ribs 14 and 15 near the fan-shaped member 13. Due to this tension area and the masseter muscle of the cheek is firmed and tightened, and the common "heavy" appearance about the cheek bone is 25 eliminated.

The upper edge of the mask extends well above the hair line of the patient, and the upper part of the mask is provided with yieldable tension distributing ribs 25 and 26 which have their source 30 at the fan-shaped member 23 to which the tension member 7 may be connected as by a suitable ring 12. The ribs 25 and 26 are tapered, both in width and thickness, and coact to adjust and firm the frontalis muscle which passes over the 35 forehead. The ribs 25 and 26 are constructed and positioned to create the area of greatest tension at that point on the forehead where are commonly found the horizontal wrinkles caused by sagging of the frontalis muscle. The ribs 26 40 are slightly curved and tapered in the direction of the area between the eyes, thus creating tension at points between the eyes and eliminating the sharp wrinkles caused by sagging and habitually faulty positioning of the corrugator muscles. 45

The dermatoid mask may be worn for definite periods at regular intervals to firm and correct faulty facial muscles, and may be easily cleaned with soap and water, or other suitable means, for use with various oil, cream, and astringent treatments. The porosity of the material used in the construction of the mask permits the skin pores to breathe easily so that wastes and poisons may be eliminated from the skin as the medications and treatments take effect. 55

I claim:

1. A dermatoid mask having elastic, porous material, tension members extending from parts of the mask to draw at a plurality of points from central portions of the mask, and ribs for directly distributing the tension over desired parts of the skin of the person. 60

2. A dermatoid mask having porous, elastic material, means for securing a part of the mask in position relative to the skin of a person, and tension members extending from other parts of the mask to draw at a plurality of points from central portions of the mask, and ribs of progressively increasing yieldability for directly distributing the tension over desired parts of the 70 skin of the person.

3. A dermatoid mask having porous, elastic material and shaped to fit the face of a person, the mask having a relatively rigid part, tension members extending from edge parts of the mask 75

- to draw at a plurality of points from central portions of the mask and the said rigid part, and ribs for directively distributing the tension over central portions of the mask.
- 5 4. A dermatoid mask having elastic, porous material, means for securing a part of the mask in position relative to the skin of a person, and tension members extending from other parts of the mask to draw at a plurality of points from 0 central portions of the mask, and elastic ribs for directively distributing the tension over desired parts of the skin of the person.
- 5 5. A dermatoid mask having porous, elastic material and shaped to fit the face of a person, a neck band at the lower part of the mask for securing said lower part in position relative to the skin of a person, tension members extending from other parts of the mask to draw at a plurality of points from central portions of the mask, and ribs 10 for directively distributing the tension over desired parts of the skin of the face of the person.
- 5 6. A dermatoid mask having porous, elastic material and shaped to fit the face of a person, a rigid rib at the lower part of the mask for securing said lower part in position relative to the skin of a person, and tension members connected to opposite points on the side edge sections of the mask to draw at the said points of connection from central portions of the mask and from the rigid rib, and 15 elastic ribs for directively distributing the tension 20 over desired parts of the skin of the person, certain of the elastic ribs extending from the lowermost point of connection and in the region of the rigid rib.
7. A dermatoid mask having porous, elastic material and shaped to fit the face of a person, a plurality of sets of yieldable, tapering ribs arranged fan-like, tension members extending from the outer ends of the ribs to draw from the central portions of the mask, the ribs operative to distribute the tension at desired degrees and over desired areas of the face of the person.
8. A dermatoid mask having porous, elastic material shaped to fit the face of a person, a plurality of sets of yieldable tapering ribs arranged fan-like, tension members extending from the outer ends of the ribs to draw from the central portions of the mask, the ribs operative to distribute the tension at desired degrees and over desired areas of the face of the person, a rigid rib at the lower part of the mask for securing said lower part in position relative to the skin of a person, a thorax band at the lower part of the mask, the said thorax band operative to secure the said lower part in position relative to the skin of the person and to distribute tension over the desired areas of the neck of the user, the tension of the 25 said thorax band being adjustable.
